ABSTRACT OF THE DISCLOSURE

A snap-action diaphragm switch for controlling the pressure of liquids or gases, wherein the operation of at least one contact spring is controlled by a pressure-actuated diaphragm which acts upon an intermediate lever connected by a snap spring to the contact spring. The diaphragm is acted upon by an adjusting spring as well as by a compensating spring which act in different directions upon this lever and produce superimposed torques.

Background of the invention

The present invention relates to an electric snap-action switch for controlling the pressure of liquids or gases and especially suitable for being employed for a clothes washing or dish-washing machine or the like, wherein this switch is provided with at least one contact spring which projects between a pair of fixed switch contacts and the operation of which may be controlled by the movements of an element, for example, a diaphragm, which is subjected to the pressure of a liquid or gas and then acts upon an intermediate control lever which is connected to the contact spring by a snap spring and is also acted upon by an adjusting spring in a direction substantially opposite to the direction of movement of the element when subjected to an increasing pressure of the liquid or gas.

In a snap-action switch of this type, the positions of the opposite change-over points or contacts of the switch, hereafter called the change and re-change points, are determined by the force of the adjusting spring acting upon the control lever in the direction opposite to the action of an element, for example, a diaphragm, which is connected to the control lever and is subjected to and movable under the changing pressure of a liquid or gas. The distance between these change and re-change points is, however, dependent upon the distance between the fixed switch contacts and also upon the elasticity constant of the adjusting spring. The minimum distance between these contacts is, in turn, dependent upon the admissible flash-over or breakdown voltage of the switch, while the maximum distance is dependent upon the geometric properties of the switch and its housing. The dimensions of the switch housing, however, also determine the dimensions of the adjusting spring which, in turn, affect the elasticity constant and the adjustability of this spring. If, therefore, the contact spring should change over from one fixed contact to the other only when a relatively strong force is exerted upon the control lever by the element, for example, a diaphragm, which is acted upon by the pressure to be controlled e.g. by a relatively high liquid or gas pressure the necessary spring force of the adjusting spring can only be attained if this spring has such a high elasticity constant that it will produce an opposing or bracing force of sufficient strength. This, however, means that the minimum distance between the change and re-change points must also be relatively large. Prior to this invention, attempts were made to overcome this difficulty by installing in each snap-action switch an adjusting spring of a strength in accordance with the particular

2

pressure to be controlled. However, since a control of high pressures also requires adjusting springs with higher elasticity constants, these known switches still had the disadvantage that the minimum distance between the change and re-change points of the contact spring also had to be relatively large.

Summary of the invention

It is an object of the present invention to provide a spring system for a snap-action switch of the character described, such that the minimum distance between the change and re-change points may be made as small as possible, while the maximum distance between the change and re-change points may be sufficiently large.

According to the invention, this object is attained by providing the snap-action switch with an additional compensating spring, a force component of which also acts upon the control lever but in a direction different from the action of the adjusting spring and exerts a torque upon the control lever which extends in the opposite direction to the torque which is exerted upon this lever by the adjusting spring.

By the provision of this compensating spring a torque is produced and exerted upon the control lever which is superimposed on the torque which is produced by the adjusting spring. Due to the pivoting movement of the control lever, this additional torque at first increases in strength and, after the control lever is pivoted for a certain distance, its strength again decreases. The increase of this torque is caused by the increase in the length of the lever moment arm which is determined by the distance between the line connecting the bearing points of the compensating spring and the pivotal axis of the control lever, whereas the decrease of this torque is caused by the release of the compensating spring.

The superimposition of the two opposing torques, one of which is produced by the adjusting spring and the other by the compensating spring, has the effect that the resultant torque line at first ascends very steeply substantially in the direction of travel of the control lever and then slopes off to some extent after the control lever reaches a central area between the minimum change point and the maximum change point. This, however, means that within the area adjacent to the re-change point and also to the minimum change point only a small resultant torque will be required for producing a movement of the control lever. Within the area adjacent to the maximum change point, however, a greater torque will be required for producing the same movement of the control lever. This operation, which prior to this invention could only be attained by employing different snap switches or by exchanging the adjusting springs for others of a different strength, may now be attained in the same snap switch by one and the same spring system, and it only requires the initial tension of the same adjusting spring to be varied when the switch is to be used for controlling different pressures. It is, however, important that, regardless of the initial tension to which the adjusting spring might be adjusted, the switch will be designed so as to permit the lowest change point and the re-change point to be spaced at a short distance from each other and also to insure that the lowest change point and the highest change point will be separated by a sufficiently large distance.

The compensating spring according to the invention is preferably provided in the form of an omega (Ω) leaf spring, one end of which is supported on a fixed or adjustable point of the switch, while its other end acts upon the control lever. In place of an omega leaf spring it is however, also possible to employ a curved leaf spring of another shape or a coil compression spring or the like. Another possibility of influencing the characteristic of the torques consists, according to the invention in pro-

viding a compensating spring which has a linear or progressive characteristic but preferably a negative or dgressive characteristic.

If a snap-action switch of the above-mentioned type is designed as a polyphase switch and provided with several identical switch systems, and if the diaphragm therefore acts upon several control levers, the additional difficulty occurs that, when one of the control levers yields under the pressure which acts upon the diaphragm, the diaphragm will tilt at an angle. This tilting of the diaphragm has the disadvantage that the tappets, which are secured to the diaphragm plate and act upon the control levers by means of a shoulder on each tappet from which a short pin projects through a bore in the respective control lever, will also tilt so that the projecting pins will engage the walls of the bores and thereby cause frictional losses which may result in an inaccurate operation of the switch.

These difficulties, which existed in previous snap-action switches, may be overcome, according to the invention, by making the supporting plate of the flexible diaphragm of a flexible material so that this supporting plate may likewise bend and therefore permit the tappets which are secured to the diaphragm supporting plate to yield laterally so that the frictional contact which previously occurred between the tappets and the control levers will be avoided.

If the switch is provided with several similar switch systems which are controlled by a common diaphragm and each of which consists of a pair of fixed contacts, a contact spring, a control lever, a snap spring, and adjusting spring, and a compensating spring, the further great advantage is attained that the switch may be easily assembled and, if desired or necessary, its individual elements may also be easily exchanged for others of the same kind.

Another advantageous feature of the invention resides in providing the outer edge portion of one of the two parts of the switch housing with an inwardly projecting bead which, when the housing is being closed, slides elastically over and behind the outwardly projecting edge of the other housing part so as to grip the latter securely. Because of this construction it is only necessary after the switch elements have been installed in the housing to press the two parts of the housing telescopically into each other so that the bead on the elastic edge portion of the one housing part will snap over the outwardly projecting edge portion of the other housing part and thereby grip the latter securely and seal the housing tightly.

The features and advantages of the present invention will become more clearly apparent from the following detailed description thereof which is to be read with reference to the accompanying drawing, in which—

FIGURE 1 shows a cross section of a single-pole switch according to the invention;

FIGURE 2 shows a cross section of a polyphase switch according to the invention;

FIGURE 3 is a diagrammatic illustration of the torques acting upon the control lever; and

FIGURE 4 is a torque diagram showing the relation of the torques to the course of movement of the control lever.

The single-pole pressure-control switch according to the invention as illustrated in FIGURE 1 comprises a diaphragm 1 which is mounted peripherally within a housing 7 and may be acted upon by the pressure of a liquid or gas entering the lower part of the switch housing through an inlet fitting 2. Diaphragm 1 carries a supporting plate 3 to which a central tappet 4 is secured; the tappet 4, in turn, acts upon a control lever 5 which is mounted at one end on housing 7 so as to be pivotable about this end in a vertical direction. At the point of connection of tappet 4 with control lever 5, the other side of this lever is acted upon by the lower end of an adjusting spring 6, the upper end of which is located within a cap 8 which

is screwed into the switch housing 7 so as to be adjustable to different levels to vary the strength of spring 6.

The control lever 5 is further associated with a contact spring 9 which is likewise secured at one end to housing 7 and provided with a longitudinal slot through which the control lever 5 may pivot from one side of contact spring 9 to the other. The free other end of contact spring carries a contact 10 which is located between the two fixed switch contacts 11 and 12 with which it is alternately adapted to engage. At a certain distance from its free end, contact spring 9 is pivotably connected to one end of a snap spring 13 in the form of a barrel spring, the other end of which is likewise pivotably connected to the free end 14 of control lever 5 in such a manner that, as soon as the control lever is pivoted and passes the plane of contact spring 9, it snaps over to the other side, thereby pivoting the contact spring 9 in the opposite direction and thus reversing the switching position or mode of contact 10 relative to the fixed contacts 11 and 12.

The free end 14 of control lever 5 is further provided with a downwardly-bent extension 15 which serves as an abutment for one end of a compensating spring 16 in the form of an omega leaf spring, the other end of which is supported on a fixed or vertically adjustable abutment 17.

The stroke of control lever 5 in the upward direction is limited by a stop projection 18 on the upper wall of housing 7, while the downward stroke of control lever 5 is limited by the lowest position of the tappet 4, that is, the position in which at a decrease of pressure on the diaphragm 1, this diaphragm rests upon the upper edge of the annular flange 19 on the bottom wall of housing 7 around the opening of the inlet 2.

FIGURE 2 illustrates a polyphase pressure-control switch according to the invention, in which the components which are similar to those in FIGURE 1 are designated by the same reference numerals. The three spring systems each of which also consists in this case of a control lever 20, a contact spring 9, a snap spring 13, and a compensating spring 16 are disposed laterally adjacent but in reverse positions to each other.

This embodiment of the invention differs further from that as previously described by the fact that the control lever which in this case is designated by the numeral 20 is bent downwardly from its fixed end so that its pivoting range lies outside of the pivoting range of contact spring 9. Contact spring 9 therefore no longer needs to be slotted to permit the control lever 20 to pivot through the contact spring. Similarly as in the first embodiment, the pivoting range of control lever 20 is limited by two stop members which in this case are designated by the numerals 21 and 22.

FIGURE 3 is a diagrammatic illustration of the forces which act upon the control lever or levers 5 or 20. First, the adjusting spring 6 exerts a pressure in the direction of the arrow J upon the control lever 5 or 20 which results in a positive torque $M_J = a \cdot J$ in a counterclockwise direction of the lever arm a which is determined by the distance between the pivot point of control lever 5 or 20 and the direction of pressure J of the adjusting spring 6 upon the control lever. Furthermore, the free end of control lever 5 or 20 is acted upon in the direction of the arrow S by the pressure of snap spring 13 which due to the lever arm b likewise results in a positive torque $M_S = b \cdot S$ in a counterclockwise direction. This lever arm b is determined by the distance between the direction of the force S from the pivot point of control lever 5 or 20. Finally, control lever 5 or 20 is acted upon the compensating spring 16 which is braced on the points 14 and 17 and exerts a pressure in the direction of the arrow K which is determined by the line of connection between the points 14 and 17 and is spaced from the pivot point of control lever 5 or 20 by a lever arm c . Due to the force K which is produced by the compensating spring

16, a negative torque $M_K = c \cdot K$ (in the clockwise direction) results; this torque is opposed to the torque which is produced and the joint action of the adjusting spring 6 and the snap spring 13.

These particular relations of the different torques acting upon the control lever 5 or 20 are indicated in greater detail in the diagram as shown in FIGURE 4, in which the course of these torques is plotted in relation to the course of travel of control lever 5 or 20 which is limited by the lower stop member 22 and the upper stop member 21. FIGURE 4 further shows, at a certain distance from the line indicating the lower stop 22, the line 23 which indicates the re-change point and must be located at a higher level than the lower stop line 22 because a positive torque must still be prevalent at the re-change point 23 in order to insure a proper engagement between the adjusting spring 6 and control lever 5 or 20. Above and parallel to this re-change point line 23, extends the line 24 which designates the lowest change point and is spaced from the lower stop line 22 at a distance A which again depends upon the distance between the switch contacts 11 and 12. Finally, the highest change point is indicated by the line 25 which, of course, lies below the line which represents the upper stop 21. The distance B between the two lines 24 and 25 indicates the range within which the desired change point may be located.

The diagram in FIGURE 4 further shows two straight inclined dotted lines M_{J_1} and M_{J_2} which represent the path of the torque $M_J = a \cdot J$ which is produced by the adjusting spring 6. These two straight lines M_{J_1} and M_{J_2} differ from each other by the fact that according to line M_{J_2} the adjusting spring 6 is given a higher initial tension and that this line is therefore shifted more to the right.

The left part of the diagram according to FIGURE 4 further indicates by a dot-and-dash line the torque curve M_K which results from the product of the force K of the compensating spring 16 multiplied by the lever arm c as indicated in FIGURE 3. This torque M_K has a negative value, and the force K of compensating spring 16 and thus also accordingly the torque M_K are of such a magnitude that the latter will be negative along the entire extent of travel of control lever 5 or 20 and that the torque line will not intersect the vertical zero line except at points above and below the two stop lines 21 and 22, respectively. As the movement of the control lever 5 or 20 progresses, the value of the torque M_K will at first increase since by the action of the upwardly moving diaphragm the control lever 5 or 20 will be pivoted in the clockwise direction which will result in a progressive increase of the length of the lever arm c and thus also in a corresponding increase of the torque M_K . When the control lever 5 or 20 has passed approximately one half of its entire distance of travel, the compensating spring 16 will be released and the spring force K will therefore be reduced to such an extent that even the further increase in the length of the lever arm c can no longer compensate this reduction of the spring force K.

As previously mentioned, the three torques M_J , M_S , and M_K are superimposed on each other. Since the torque M_S which is produced by snap spring 13 is relatively small, it will be neglected in the following observations. When the torque M_K is then superimposed on the two torques M_{J_1} and M_{J_2} , the two torque lines $(M_K + M_{J_1})$ and $(M_K + M_{J_2})$ will result which are shown by solid lines in FIGURE 4. These two equal torque lines $(M_K + M_{J_1})$ and $(M_K + M_{J_2})$ at first ascend very steeply and their slope then decreases approximately within their central part. This curving of the torque lines $(M_K + M_{J_1})$ and $(M_K + M_{J_2})$ is caused entirely by the course of the torque line M_K .

A comparison, for example, of the course of the torque line $(M_K + M_{S_1})$ with the course of the torque line M_{J_1} shows that, if the control lever 5 or 20 should travel the distance A, a considerably smaller torque will be 75

required than when merely the adjusting spring 6 were present which produces the torque M_{J_1} . Since a linear relation exists between these torques and the opposing force which is exerted by the diaphragm 1, and thus also between these torques and the pressure which is exerted upon the diaphragm, it is manifest that the lowest change point 24 may be placed at a very small distance from the re-change point 23. For pivoting the control lever 5 or 20 to the highest change point 25, it is, however, necessary to provide considerably larger torques.

If the change points 23, 24, and 25 are to be shifted upwardly, it is necessary to give the adjusting spring 6 an initial tension so that the line M_J and thus also the line $(M_K + M_J)$ will be shifted farther toward the right. The distances A and B between the re-change point 23 and the lowest change point 24 and between the lowest change point 24 and the highest change point 25 remain, however, the same which may also be seen from the following numerical example:

If the re-change point 23 is located within the torque line $(M_K + M_{J_1})$, for example, at a pressure of 20 mm. W.G., the lowest change point 24 may already occur at a pressure of 50 mm. W.G. so that the difference only amounts to 30 mm. W.G. The highest change point 25, however, occurs in this case at a pressure of 100 mm. W.G. If the adjusting spring 6 is then adjusted to have a higher tension, greater switching forces will be required which, in turn, require higher pressures which would then have to amount to, for example, 120 mm. W.G., 150 mm. W.G., and 200 mm. W.G. It is then, however, essential that at such high change points the pressure differences A and B, and especially the small pressure differences A between the re-change point 23 and the lower change point 24 will remain unchanged. When employing only one adjusting spring 6 and one compensating spring 16, it is therefore possible to attain low as well as high change points, even though the small pressure differences A between the re-change point 23 and the lowest change point 24 remain unchanged.

If the slope of the upper range of the torque line $(M_K + M_J)$ should be still less inclined, this may be attained by employing a compensating spring 16 with a digressive characteristic.

As further illustrated in FIGURES 1 and 2, the diaphragm 1 is provided with a thicker outer ring 26 which is clamped between the two opposite annular surfaces 27 and 28 of the upper housing part 7 and the lower housing part 29. This lower housing part 29 which is preferably made of plastic has an outer rim 30 which encloses and projects upwardly from the outer ring 26 of diaphragm 1 and is slightly elastic. On its upper edge, it has an inwardly projecting bead 31 which, when the two-part switch housing is closed, snaps over the outer edge 32 of the upper housing part 7 and thus connects the two housing parts 7 and 29 tightly to each other. In order to permit the upper housing part 7 to be easily pressed into the lower housing part 29 when the switch is being installed, the inner edge 33 of bead 31 is inwardly inclined in the manner as shown in FIGURES 1 and 2.

For properly supporting the diaphragm 1 especially in the polyphase switch according to FIGURE 2, the tappets 4 on the diaphragm plate 3 project loosely through bores 34 which are provided in the control levers 20. A three-point support of the control levers 20 on the diaphragm plate 3 is attained by providing not only a second, only partly indicated switch system behind the system which is completely shown in FIGURE 2 but also a third switch system which is located in front of the plane of the drawing. Since each of the adjusting springs 6 of the three switch systems is supported at its upper end within a cap 8 which is screwed into the upper housing part 7 so as to permit it to be adjusted to different levels, it is possible to adjust the three adjusting springs 6 to different initial tensions which, in turn means that the forces which are exerted by the adjusting springs 6 so as

to brace the diaphragm 1 will be of different strengths and that, as soon as a pressure is exerted upon the diaphragm 1, this pressure will overcome the force of that adjusting spring 6 which has the lowest initial tension. This, in turn, means that the diaphragm 1 will be partly lifted and bent, provided the diaphragm-supporting plate 3 is made according to the invention of an elastic material and is therefore capable of yielding when so moved. This, however, insures that the tappets 4 which project through the bores 33 in the control levers 20 will not jam therein and that therefore also no undue friction will occur between the tappets and the walls of bores 33.

Although my invention has been illustrated and described with reference to the preferred embodiments thereof, I wish to have it understood that it is in no way limited to the details of such embodiments but is capable of numerous modifications within the scope of the appended claims.

Having thus fully disclosed my invention, what I claim is:

1. An electric snap-action switch for controlling the pressure of liquids or gases, comprising a housing, a diaphragm peripherally and tightly secured to the outer wall of said housing and dividing the same into a first part and a second part, said first housing part having an inlet opening through which the pressure to be controlled may enter said first housing part and act upon one side of said diaphragm so as to shift said diaphragm in the direction of said second housing part, at least one pair of fixed contacts mounted in said second part and spaced from each other, at least one contact spring having a fixed end mounted on said housing within said second part and a free end projecting between said fixed contacts and adapted to engage with one of said contacts when said pressure is below a certain value and with the other contact when said pressure increases above said value, at least one control lever having one end connected to said housing adjacent to the fixed end of said contact spring and pivotable at said fixed end relative to said contact spring, at least one tappet having one end secured to said diaphragm and another end engaging one side of said control lever, at least one adjusting spring having one end secured to said housing and another end engaging the other side of said control lever so as to exert a torque thereon, means for varying the strength of said adjusting spring in a predetermined relation to the pressure to be controlled, a snap spring having an axis normally extending to said control lever and said contact spring and interconnecting said control lever and said contact spring, said snap spring being adapted when said pressure increases beyond said value and said lever is pivoted in a first direction together with said lever and thereby to pivot said contact spring quickly in the opposite second direction and from engagement with the first into engagement with the second fixed contact, said snap spring being further adapted when said pressure decreases below said value to snap over in said second direction together with said lever and thereby to pivot said contact spring in said first direction and from engagement with said second into engagement with said first contact,

and a compensating spring having a force component acting upon said lever in a direction different from the action of said adjusting spring and exerting a torque upon said lever extending in the opposite direction to said torque exerted thereon by said adjusting spring.

5 2. A switch as defined in claim 1, wherein said compensating spring is a curved leaf spring one end of which is supported on a fixed part of said switch, while the other end of said curved leaf spring acts upon said control lever.

3. A switch as defined in claim 1, wherein said compensating spring has a degressive characteristic.

15 4. A switch as defined in claim 1, further comprising fixed stop members for limiting the pivoting range of said control lever.

5 5. A switch as defined in claim 1, wherein said contact spring is provided with a longitudinal slot and said control lever is pivotable through said slot from one side of said contact spring to the other.

20 6. A switch as defined in claim 1, wherein said control lever is bent in such a manner that its pivoting range is located outside of the pivoting range of said contact spring.

25 7. A switch as defined in claim 1 and forming a polyphase switch assembly having a plurality of switch systems all of which are acted upon by said one diaphragm and each comprising a pair of said fixed contacts, said contact spring, said control lever, said snap spring, said adjusting spring and said compensating spring.

30 8. A switch as defined in claim 7, wherein said switch systems are disposed laterally adjacent but in reverse positions to each other.

35 9. A switch as defined in claim 7, further comprising a flexible plate on said diaphragm for supporting the same, said tappets for acting upon said control levers of said switch systems being secured to said supporting plate.

40 10. A switch as defined in claim 1, wherein said housing consists of separate upper and lower parts, one of said housing parts having an outer edge portion with a bead thereon projecting in one direction, and the other housing part having an outer edge portion projecting in the opposite direction, said bead being adapted to snap elastically over the outer edge portion of said other housing part when said two housing parts are telescopically connected to each other.
